pany, Seattle, Wash., a corporation of Delaware

Filed Jan. 9, 1961, Ser. No. 63,596

Term of patent 14 years

(Cl. D71—1)

Fig. 3

Fig. 4

FIG. 1 is a side elevation of a rotary wing aircraft embodying our new design;

FIG. 2 is a top plan view thereof with portions of the wings broken away for convenience of illustration;

FIGS. 3 and 4 are front and rear elevations, respectively, of the aircraft; and

FIG. 5 is a front perspective view thereof, taken from the top.

The dominant features of our design reside in the portions shown in full lines, with portions of the rotor blades being shown broken away in all views for convenience of illustration only.

We claim:

The ornamental design for a rotary wing aircraft, substantially as shown and described.
